UNITED STATES PATENT OFFICE

2,393,418

GATE

Emmett B. Sawyer, Fort Belvoir, Va.

Application March 22, 1945, Serial No. 584,085

1 Claim. (Cl. 39—56)

This invention relates to that type of gate which is provided with upper and lower hinges, the lower hinge being in the form of a pintle seated in a horizontally shiftable carriage, so that when the carriage is shifted laterally of the gate, the latter is thrown out of plumb so that it will swing open by gravity.

The primary object of the present invention is to provide, in a gate of the above kind, improved means for mounting the gate so that it may be thrown out of plumb, and improved means operable by the wheel of a vehicle for shifting the carriage to throw the gate out of plumb.

Other objects and features of the invention will become apparent from the following description when considered in connection with the accompanying drawing, and the invention consists in the novel form, combination and arrangement of parts hereinafter more fully described, shown in the drawing and claimed.

In the drawing, wherein like reference characters indicate corresponding parts throughout the several views:

Figure 1 is a perspective view showing an embodiment of the present invention.

Figures 2 and 3 are somewhat diagrammatic views showing the gate proper in end elevation and respectively illustrating the gate in a plumb position and in an out-of-plumb position.

Figure 4 is a fragmentary detail view illustrating the lower hinge of the gate and showing the shiftable carriage and adjacent parts in longitudinal section.

Figure 5 is an enlarged transverse section taken on the line 5—5 of Figure 4.

Referring in detail to the drawing, the gate proper is shown as composed of an upright bar 5 at the hinging end and a similar bar 6 at the latching end, said bars 5 and 6 being rigidly connected by horizontal bars or slats 7. The gate is associated with a hinging post 8 and a latching post 9. The gate is hinged to the post 8 by means of a pintle 10 extending vertically from the top of the bar 5 through an aperture of an angle bracket 11 secured to the upper portion of the post 8. The bar 5 is provided at the bottom with a depending vertical pintle 12 that is seated in a shallow recess 13 formed centrally in the upper face of a horizontally shiftable carriage 14 reciprocable in an elongated recess 15 provided in a base 16. The arrangement is such that the carriage 14 may be moved in either direction laterally of the post 8 to

throw the gate out of plumb so that it will swing open by gravity in a well known way.

As shown, the base 16 includes a plank 17 laid and suitably secured upon the driveway along one side of the latter, and a board or plate 18 secured upon the plank 17 intermediate its ends, said plate or board 18 having a central relatively large rectangular opening which is closed at the bottom by the plank 17 to form the recess 15 in which carriage 14 is slidably arranged. Suitable tension springs 19 are interposed between the ends of the carriage 14 and the adjacent end walls of the recess 15 to yieldingly maintain the carriage normally midway between the ends of said recess 15, as shown in Figure 4. When the carriage is in this normal position, the gate is in a vertical or plumb position, as shown in Figure 2. Easy movement of the carriage 14 is promoted by providing the same with bottom antifriction rollers 20 arranged to ride on the bottom of the recess 15 and side antifriction rollers 21 arranged to ride on the side walls of the recess 15, as clearly shown in Figures 4 and 5. In Figure 3, the carriage 14 is shown in a position shifted to the right of the figure which results in throwing the gate out of plumb so that it will swing open by gravity to the left of the figure, as indicated by dotted lines. Of course, the pintle 10 will be slightly loose in the bracket 11 to permit this lateral tilting of the gate due to horizontal shifting of the carriage 14.

It will be noted that the plank 17 extends a considerable distance beyond each side of the gate. As a means for moving the carriage 14, I connect one end of a cord 22 to one end of the carriage 14, passing said cord away from the adjacent side of the gate, under a guide 23 mounted on the plank 17, and to an eye 24 of an inclined, upwardly projecting crank arm 25 provided on one end of a rock shaft 26 journaled transversely upon the plank 17 by bearings 27. The crank shaft 26 is located near an end of the plank 17 and at a suitable distance from the gate, and the inner end of the shaft 26 is formed with a crank in the form of a trip plate 28 projecting from the shaft 26 in a direction away from the gate. The springs 19 are assisted by further springs 29 in normally positioning the parts so that the carriage 14 is located midway between the ends of recess 15 and the trip plate 28 is slightly elevated above the surface of the driveway. From the eye 24, the cord 22 may be extended back to the bar 5 at the hinging end of the gate where it passes around a guide 30 and then extends to and is connected with a piv-

oted latch 31 engageable with a catch on the latching post 9, as is well known in the art.

The arrangement is such that when the wheel of a vehicle passes over the trip plate 28, it depresses the latter and rocks shaft 26 in a direction to cause crank arm 25 to exert a pull on the cord 22, thereby raising and releasing the latch 31 and shifting the carriage 14 toward the vehicle. This results in throwing the gate out of plumb so that it will automatically open by gravity in a direction away from the vehicle. The same carriage shifting and latch-releasing means is provided at both sides of the gate so that the gate may be unlatched and opened by a vehicle approaching the gate from either direction. If desired, a suitable ramp 32 may be provided at the approach end of each trip plate 28 to facilitate riding of the vehicle wheel onto the latter.

By constructing the base 16 in the manner shown and described, the plank 17 provides a mounting for both crank shafts 26, the guides 23, and the attaching means for the lower ends of the springs 29. In conjunction with the plate or board 18, it provides a cheap and inexpensive 25

construction for affording the recess 15 in which the carriage 14 moves.

From the foregoing description, it is believed that the construction, operation and advantages of the present invention will be readily understood and appreciated by those skilled in the art. Minor changes may be made in details of construction illustrated and described, such as fairly fall within the spirit and scope of the invention as claimed.

What I claim is:

The combination with a vertical hinge bar of a gate having a pintle depending from its lower end, a base provided with a recess, a carriage horizontally slideable in said recess and having said pintle seated therein, tension springs connected to opposite ends of the carriage to normally position the latter with the gate in a plumb position, and means connected with the ends of the carriage to slide the same longitudinally, said means including trip plates arranged to be depressed by riding of a vehicle wheel thereover and mounted at opposite sides of the gate.

EMMETT B. SAWYER.
